[57] CLAIM

The ornamental design for a wood blank with desk top art, as shown and described.

DESCRIPTION

FIG. 1 is an environmental perspective view of a wood blank with desk top art showing my new design;

FIG. 2 is a right side elevational view with the left side being a mirror image thereof;

FIG. 3 is a front elevational view with the rear being a mirror image thereof; and,

FIG. 4 is a top view thereof.

The broken line showing of the desk in FIGS. 1-3 is for illustrative purposes only and forms no part of the claimed design.
